I. E. PALMER,
FASTENER FOR COUCH HAMMOCKS AND OTHER STRUCTURES,
APPLICATION FILED JULY 24, 1911.

1,234,207.

Patented July 24, 1917.

UNITED STATES PATENT OFFICE.

ISAAC E. PALMER, OF MIDDLETOWN, CONNECTICUT, ASSIGNOR TO THE I. E. PALMER CO., OF MIDDLETOWN, CONNECTICUT, A CORPORATION OF CONNECTICUT.

FASTENER FOR COUCH-HAMMOCKS AND OTHER STRUCTURES.

1,234,207.

Specification of Letters Patent. Patented July 24, 1917.

Application filed July 24, 1911. Serial No. 640,132.

To all whom it may concern:

Be it known that I, ISAAC E. PALMER, a citizen of the United States, and a resident of Middletown, in the county of Middlesex and State of Connecticut, have invented an Improvement in Fasteners for Couch-Hammocks and other Structures, of which the following description, in connection with the accompanying drawings, is a specification, like characters on the drawings representing like parts.

This invention relates to fasteners for couch hammocks and other structures. The invention is particularly applicable to couch hammocks, but in certain aspects thereof is capable of use in other relations.

In order that the principle of the invention may be readily understood, I have shown certain embodiments thereof and the application of my invention to couch hammocks in the accompanying drawings, wherein—

Figure 1 is a perspective view of a couch hammock having my invention applied thereto;

Fig. 2 is a view mainly in elevation of a portion of one suspension end and of the wind shield of a couch hammock having my invention applied thereto;

Fig. 2^a is a view in side elevation of one of the eyes constituting a portion of my invention;

Fig. 3 is a detail of the hook and eye shown in Fig. 2;

Fig. 4 is a view similar to Fig. 2 of a modified form of my invention;

Fig. 5 is a detail of that form of my invention shown in Fig. 4;

Fig. 6 is a section upon the line 6—6 of Fig. 2;

Fig. 7 is a section upon the line 7—7 of Fig. 4;

Fig. 8 is a plan view and Fig. 9 a section of another form of my invention particularly adapted for attaching parts of a couch hammock to be positioned in the same plane; and

Figs. 10 and 11 are similar views of a modified form thereof.

Couch hammocks have heretofore been provided with wind shields or the like connected by lacing to the suspension ends thereof. I have devised certain hook and eye means peculiarly adapted for attaching the wind shield of a couch hammock to the

suspension ends, and also for attaching the lower edge of the wind shield to the body of the couch hammock, as, for example, to the rear upstanding edge thereof. Such hook and eye means, while serviceable in certain other relations, are peculiarly adapted to couch hammocks, as they permit the ready separation of the wind shield or the like from the body of the hammock and also permit the same to be readily connected thereto and held in position without wrinkling or undue pull upon either the suspension ends or the wind shield.

Referring more particularly to the drawings, I have in Figs. 1 and 2 disclosed a couch hammock to which my invention may be applied and having suspension ends 1—1, upstanding sides 2—2, a frame 3 composed of side and end members, a mattress 4 and stringing means 5—5. Obviously said suspension ends may be continuous beneath the frame or may be discontinuous and connected if desired to the end members of the frame. The structure of the hammock as thus far described is immaterial. I have shown one of the upstanding sides 2 as connected by lacing 6 to the end members of the frame, but obviously I may employ the hook and eye means hereinafter described for such purpose.

In Fig. 1 I have represented a wind shield 7 which may be of ordinary construction except as hereinafter described. Instead of connecting said wind shield to the suspension ends 1 by means of lacing, I have provided one or the other of said parts, and herein the suspension ends 1, with eyes 8, 9, 10, preferably metallic, and secured along one or both vertical edges of said ends. If desired, however, the said eyes may be mere openings in the edges of said ends and may be "worked" in the manner customary in connection with button holes. It will be noted that the eyes 9, 10 are longer than the eye 8, this construction being preferably resorted to to prevent wrinkling of either the wind shield or the suspension ends when the parts are connected, which wrinkling might occur if the hooks and eyes were not positioned absolutely true with respect to each other. If desired, all of the eyes may be thus elongated.

As indicated most clearly in Fig. 2^a, each of the eyes is preferably composed of a metal member having prongs 11 at its four

corners adapted to penetrate the textile material of the suspension ends and to be upset thereagainst. Preferably the prongs are of such length that the face of the eye is held slightly removed from the face of the textile material thereby permitting the insertion of the end or head of the hook into the eye.

That form of my invention shown in Figs. 2, 3 and 6, is particularly adapted for use in connection with parts which when positioned are to be held at an angle to each other, and preferably a right angle, as is the case in connection with the suspension ends and wind shield of a couch hammock. In Figs. 3 and 6, the wind shield 7 is provided with a preferably metallic hook 12 having a spur or prong 13 at one end penetrating the material of the wind shield and upset against a face thereof. The body 14 of the hook may be enlarged as indicated in Fig. 3 and is prolonged into a double head 15, the structure whereof is shown most clearly in Fig. 6. This head is adapted to be inserted into the eye 8 by positioning said double head so that the longest dimension of said head is in parallelism with the longitudinal axis of the eye 8, and then inserting said head into said eye, after which the head and cloth or other part to which it is secured are twisted through ninety degrees, so as to bring the wind shield into its desired right angular relation with respect to the suspension end 1 with the head extending transversely of the eye. In a similar manner, the other hooks are inserted into the eyes 9, 10. The employment of any particular number of hooks and eyes is, however, immaterial. Preferably, however, a plurality thereof is employed.

If desired and as indicated in Fig. 2, one at least of the eyes is elongated so as to permit the uniting of the wind shield and suspension end without wrinkling either part in case the hooks and eyes be not accurately positioned.

In Figs. 4, 5 and 7, I have indicated a slightly different form of my invention, wherein the eye 16 is a gromet eye set into a preferably elongated slit or opening in the edge of one of the parts. The hook 17 may be of the form shown, it being preferably metallic and secured by a gromet eye 18 or otherwise to the companion part. At its outer end it is provided with a head 19 similar it may be to the head 15 previously described. As shown in Fig. 4, one at least of the eyes 16 is elongated for reasons already described.

The forms of hooks thus far described are particularly intended for uniting parts which normally are positioned in an angular relation with respect to each other, such, for example, as a right angle.

In Figs. 8 to 11, I have indicated a further

form of my invention particularly intended for connecting parts normally positioned in the same plane, as for example, the wind shield of a couch hammock and one of the upstanding sides, as indicated in Fig. 1. In Figs. 8 and 9, I have indicated an eye 20 similar it may be to the eye 16 of Fig. 5, said eye being a gromet or other eye upon one of the parts. To the companion part is secured a hook 21 by a gromet 22 or otherwise, said eye being bent at substantially right angles at an intermediate point 23 of its length. At its extreme free end the hook is provided with a transverse preferably double head 24 as indicated most clearly in Fig. 8.

The construction shown in Figs. 10 and 11 differs from that shown in Figs. 8 and 9 substantially only in that the eye 20' is positioned with its longest dimension in parallelism with the edge of the fabric, as indicated in Fig. 10, and in that the hook 21 is curved as indicated at 25 instead of sharply bent as indicated in Fig. 9. At its outer end it is provided with a preferably double head 26, the longest dimension of which lies in or parallel with the longest dimension of the said hook.

In using the hook and eye shown in Figs. 8 and 9, the fabric or part having the hook 21 is twisted until the head 24 lies with its longest dimension in parallelism with the eye 20. The head 24 is then inserted through said eye, and the fabric or part twisted about until the head 24 lies transversely of the eye 20, in which position of the hook the parts carrying the hook and eye will be positioned in the same plane or in parallelism. The use of the hook and eye shown in Figs. 10 and 11 is substantially similar to that of the hook and eye shown in Figs. 8 and 9, the parts being brought into parallelism or into the same plane when in normal position. As previously stated, it is evident that my invention is not restricted in use to couch hammocks, although it is of peculiar applicability thereto, in that it provides a ready means for connecting the parts normally positioned at either right angles or in parallelism with respect to each other.

It is evident that the hooks may be placed upon either the suspension ends or the wind shield, and also that either the lower edge of the wind shield or the upper edge of the upstanding side may be provided with the hook or hooks.

Having thus described one illustrative embodiment of my invention, I desire it to be understood, that although specific terms are employed, they are used in a generic and descriptive sense and not for purposes of limitation, the scope of the invention being set forth in the following claims.

Claims:

1. A couch hammock having a frame, a

- 5 fabric wind shield extending longitudinally of the couch hammock frame, a fabric body portion distinct from said wind shield and having an upwardly extending edge meeting the lower edge of said wind shield, said meeting edges being provided, the one with one or more eyes extending wholly through the fabric, and the other with a corresponding number of hooks secured flatwise thereon 10 to and each provided with a bent prolongation terminating in a transverse head extending beyond the edge of the fabric piece to which it is secured and adapted to be inserted in the corresponding eye, whereby 15 the two fabric pieces may be relatively twisted for the insertion of the hook or hooks in the eye or eyes, and then brought into the same plane in face contact with each other.
- 20 2. A couch hammock having corner fastenings for securing together at right angles the fabric suspension ends and the wind shield thereof, the fastening at each end of the hammock comprising an elongated eyelet member secured to one of said parts adjacent the upright edge thereof with the longer dimension of said eyelet member in substantial parallelism with said upright edge, and a hook member secured to the 25 other of said parts adjacent its upright edge,
- 30 said hook member having a securing base and a narrow body portion prolonged beyond said securing base in substantial parallelism with the plane of the part to which it is secured and extending beyond the upright edge of said part, said body portion terminating in a double cross head rigid with and extending transversely of said body portion, said cross head being of a length substantially corresponding with the 35 longer dimension of said eyelet member, whereby, by insertion of said hook members in said eyelet members and the subsequent relative twisting of said parts through substantially 90°, the wind shield is supported 40 in right-angled relation to said suspension ends, the lower edge of said wind shield and the upstanding rear edge of the couch hammock having detachable hook and eyelet connections positioned to support said parts 45 in substantially the same vertical plane, said wind shield being thereby detachably supported at its ends and lower edge.
- In testimony whereof, I have signed my name to this specification, in the presence of 50 two subscribing witnesses.
- ISAAC E. PALMER.
